[57] CLAIM

The ornamental design for a cap, as shown and described.

DESCRIPTION

FIG. 1 is a front perspective view of a cap showing my new design;

FIG. 2 is a top plan view thereof;

FIG. 3 is a front elevational view thereof;

FIG. 4 is a side elevational view thereof, the opposite side is a mirror image;

FIG. 5 is a rear elevational view thereof; and,

FIG. 6 is a bottom plan view thereof.

The broken line showing the human form in FIG. 1 is for illustrative purposes only and forms no part of the claimed design.
